UNITED STATES PATENT OFFICE.

EDWIN E. LEHR, OF WILKINSBURG, PENNSYLVANIA, ASSIGNOR TO WESTINGHOUSE ELECTRIC & MANUFACTURING COMPANY, A CORPORATION OF PENNSYLVANIA.

REGULATOR SYSTEM.

Application filed June 16, 1922, Serial No. 568,730. Renewed June 23, 1925.

To all whom it may concern:

Be it known that I, EDWIN E. LEHR, a citizen of the United States, and a resident of Wilkinsburg, in the county of Allegheny and State of Pennsylvania, have invented a new and useful Improvement in Regulator Systems, of which the following is a specification.

My invention relates to regulator systems and it has special relation to induction regulator control systems and apparatus.

One object of my invention is to provide a control system for an induction regulator with new and improved apparatus which will speed up the operation of the regulator in correcting for voltage variations upon the power circuit to which the same is connected, and also minimize unnecessary operation of the regulator.

The voltage variations encountered in power-circuit operation which need to be corrected for are, first, those caused by slow changes on the system, of small value such as a fraction of a volt, and second, those more abrupt and wider voltage variations. The first set of changes are not immediately perceptible in their effects upon the power circuit and the dynamo-electric machines connected thereto, but need to be corrected for if of continued duration, while the second group of corrections need to be corrected for as rapidly as possible.

More specifically, my invention comprises improvements upon the invention of S. D. Sprong, filed February 20, 1922, Serial No. 537,859, and assigned to the Westinghouse Electric & Manufacturing Company. In that application is suggested the use of a damped electromagnet and an undamped electromagnet, both of which are energized in accordance with the characteristic of the power circuit being regulated. Said electromagnets are adapted to control the operation of co-operating contact members and means for preventing hunting action of the induction regulators is also provided.

The present invention embodies the principles set forth in said application, and involves improving the apparatus and the operation thereof by mounting one set of contact members upon a relatively long arm

and mounting the second set of contact members upon a relatively short arm.

The present invention also contemplates providing compounding coils for preventing 55 chattering of the contact members.

Reference may now be had to the accompanying drawings, wherein—

Figure 1 is a front elevation of a panel board containing the new control apparatus; 60

Fig. 2 is a side elevation, partly in section, of the apparatus of Fig. 1; and

Fig. 3 is a diagrammatic illustration of an induction regulator control system embodying the apparatus of the present invention. 65

Referring to Fig. 3, an induction regulator 1, embodying a current coil 2 and a voltage coil 3, is operatively connected to a power circuit comprising conductors 4 and 5. The induction regulator 1 may be operated by means of a motor 6 through reversing switches 7 and 8. The reversing switches are adapted to be selectively operated by means of the apparatus illustrated in Fig. 1. 75

This apparatus embodies an electromagnet 9 having a core armature 11 pivotally secured to one end of a lever arm 12. The lever arm 12 is pivoted at 13 in a bracket 14 and has co-operating with the free end 80 thereof a spring 15 that is secured at its other end to a screw 16, adjustable within a bracket 17. The arm 12 has riveted thereto a plate 18 which carries a bent leaf spring 19 that overlies the plate 18, as will be seen 85 best from Fig. 2. The spring 19 carries a contact member 21. A contact member 22 is mounted on the opposite side of the pivot 13 in a similar manner to that described for the contact member 21. 90

An electromagnet 23, which is connected in circuit with the electromagnet 9, has a core armature 24 that is pivotally secured to a lever arm 25. The lever arm 25 is pivoted at 26 to the bracket 14. The core 95 armature 24 has co-operating with the free end thereof a time-element device, such as a two-way dash-pot 27, the action of which may be regulated by means of thumb screws 28 in a well-known manner. 100

A flat spring 29 has its central portion secured to the lever 25 by means of screws

31, illustrated in dotted lines in Fig. 1. The respective ends of the spring 29 carry contact members 32 and 33, which are adapted to co-operate with contact members 22 and 5 21, respectively. Adjustable screws 34 and 35 are carried by the arm 25 and respectively co-operate with the contact members 32 and 33, thereby rendering it possible to adjust the position of these contact members.

10 A coil spring 36, which is adjustable by means of a screw 37 operating in bracket 38, is secured near one end of, and co-operates with the arm 25. The pull of the spring 36 counterbalances the pull of the 15 electromagnet 23.

The lever arm 12 has mounted upon the opposite ends thereof armatures 41 and 42, which are adapted to be attracted by the energization of electromagnets 43 and 44 20 that are located above said armatures, each time the illustrated control apparatus is operated. The purpose of the electromagnets 43 and 44 is to selectively attract the armatures 41 and 42 to prevent chattering 25 of the contact members.

The bracket 14 is secured to a panel board 45 by means of screws 46, as best shown in Fig. 2. The electromagnets 9 and 23 are secured to the panel board 45 by means of 30 brackets 47 and screws 48. The dash-pot mechanism 27 is secured to the panel board 45 by means of bolts 49. The panel board 49 is secured within a casing 51, by means of screws 53. The casing has a glass front 52.

35 The coils of the electromagnets 9 and 23 are adapted to be energized in accordance with the voltage of the power circuit through transformer 54. (See Fig. 3.)

The lever arm 12, upon which are mounted 40 contact members 21 and 22, is relatively long, while the lever arm 25, upon which are mounted contact members 32 and 33, is relatively short. The electromagnet 9, actuating the longer lever arm 12, is undamped, and the electromagnet 23, actuating the shorter lever arm 25, is damped. For a particular voltage change in the 45 circuit energizing magnets 9 and 23, the armatures 11 and 24 will correspondingly change 50 their positions. Since, however, the lever arm 12 is longer than the lever arm 25, it will make a smaller angular movement, and, consequently, the contact members 21 and 22 will move a lesser degree than the 55 contact members 32 and 33.

If a slight change in voltage exists for a short time only, the cooperating contact members on the arms 12 and 25 will not be engaged, since the long arm 12 will move 60 only a slight amount, and the short arm 25, having a damped action, will move slowly. Should, however, the changed condition be maintained, the contacts will close and effect the regulation. If a decided 65 change in voltage occurs, the undamped

magnet 9 will actuate the lever 12 sufficiently to immediately close the contacts.

The operation of the apparatus is substantially as follows:—

Assume that the normal gap between each 70 pair of contact members corresponds to $\frac{3}{4}$ volt, it being understood that the distance between the contact members determines the permissible voltage variation upon the power circuit.

Assume now that there is an abrupt voltage variation of $1\frac{1}{4}$ volts upon the power circuit 4, 5. The electromagnet 9 will be instantaneously actuated. However, because of the long-radius sectors to be traversed 75 by the arm 12, the contact members 22 and 32 fail to engage each other. While the electromagnet 23 is simultaneously energized with the electromagnet 9, it cannot instantaneously move the contact member 80 32, because of the damping action of the dash-pot 27. Accordingly, there will be no operation of the induction regulator to correct for this abrupt voltage variation.

If the variation is of long enough duration to permit the electromagnet 23 to move the contact arm 25 a sufficient distance to effect engagement of the contact members 32 and 22, the induction regulator will be operated to correct for the variation. It 90 will be understood that the apparatus is so designed that a voltage variation is not permitted to exist for a length of time sufficient to have a damaging effect upon the power circuit or the apparatus connected thereto. 95 It will be further noted that the co-operating contact members are moved toward each other to effect the corrective operation of the regulator.

Next, assume a voltage variation of $\frac{3}{4}$ volt of extended duration. The electromagnet 9 will be instantaneously energized, but, because of the weight of the arm 12 and the length thereof, this small variation will not be sufficient to move the contact member 100 22. However, the electromagnet 23 will operate the arm 25 to effect engagement between the contact members 32 and 22 as soon as the time element of the dash-pot 27 105 is overcome. It will be noted that the regulator has not been operated to correct for the assumed small voltage variation until it has existed for a predetermined length of time, which time is long enough to insure 110 that the variation is more than temporary and, therefore, should be corrected for.

Next, assume an abrupt voltage variation of $1\frac{3}{4}$ volts. The electromagnet 9 will be immediately operated to cause engagement 115 of the contact members 22 and 32 without any movement on the part of the contact member 32, which is under control of the electromagnet 23. Of course, the simultaneously energized electromagnet 23 will shortly 120 effect a movement of the contact member 125 130

32 in the direction of the contact member 22, which action will merely insure more perfect contact.

- From the foregoing description, it will 5 be apparent that the control apparatus has only been described as effecting engagement between the contact members 22 and 32, which is the correct operation for an increase in voltage upon the power circuit. 10 However, it will be understood that the apparatus operates in the same manner, except in the opposite direction, to effect engagement between the contact members 33 and 21 upon a decrease in voltage upon the 15 power circuit.

Hunting action of the regulator is prevented in each instance, since the undamped electromagnet 9 immediately responds to the return of the voltage upon the power 20 circuit to its normal value, and this immediate response will cause prompt disengagement of the engaged contact members. In each of the assumed corrections, the normal operation of the system is for the contact 25 members to selectively energize the reversing switches 7 and 8 to rotate the motor 6 in one direction or the other, in accordance with a familiar practice.

By eliminating the unnecessary functioning 30 of the regulator with a close setting of the contact members of the control apparatus, the tendency of the regulator to overrun is eliminated and it has become possible to speed up the corrective operation of the 35 regulator.

Modifications in the system and arrangement and location of parts may be made within the spirit and scope of my invention, and such modifications are intended to be 40 covered by the appended claims.

I claim as my invention:—

1. In a regulator system, the combination 45 with a power circuit and an induction regulator connected thereto, of control means therefor comprising an electromagnet, a relatively short contact-carrying arm controlled thereby, time-element mechanism co-operating with said electromagnet, a second electromagnet connected in circuit with the 50 first-mentioned electromagnet and a relatively long contact-carrying arm controlled thereby, each contact-carrying arm being provided with a plurality of co-operating contact members.

55 2. In a regulator system, the combination with a power circuit and an induction regulator connected thereto, of control means therefor comprising an electromagnet, a relatively short arm controlled thereby carrying a plurality of contact members, a second electromagnet, a relatively long arm controlled thereby carrying a plurality of co-operating contact members, said contact mechanism being controlled by the operations 60 of said electromagnets to govern the

operation of the induction regulator in the one direction or in the other direction.

3. In a regulator system, the combination with a power circuit and an induction regulator connected thereto, of control means 70 therefor comprising an electromagnet energized in accordance with a characteristic of said power circuit, a second electromagnet connected in circuit with the first-mentioned electromagnet, and means controlled by said electromagnets to respectively receive relatively small and relatively large movements whereby the control of the operation of said induction regulator is initiated after varying time intervals. 75

4. In a regulator system, the combination with a power circuit and an induction regulator connected thereto, of control means therefor comprising an electromagnet energized in accordance with a characteristic of 80 said power circuit, a second electromagnet connected in circuit with the first-mentioned electromagnet, means controlled by said electromagnets to respectively receive relatively small and relatively large movements whereby the control of the operation of said induction regulator is initiated after varying time intervals, and means for preventing 85 hunting action.

5. In a regulator system, the combination 90 with a power circuit and an induction regulator connected thereto, of control means therefor comprising a damped electromagnet, a relatively short arm controlled thereby, a pair of contact members controlled 95 by said arm, an undamped electromagnet, a relatively long arm controlled thereby and a pair of contact members controlled by said arm, said electromagnets co-operating to selectively control the engagement 100 of said contact members.

6. In a regulator system, the combination 105 with a power circuit and an induction regulator connected thereto, of control means therefor comprising a damped electromagnet, means controlled thereby having a relatively small movement, contact members controlled by said means, an undamped electromagnet, means controlled thereby having a relatively large movement, and contact members controlled thereby, said electromagnets selectively controlling the 110 engagement of said contact members.

7. In a regulator system, the combination 115 with a power circuit and an induction regulator connected thereto, of control means therefor adapted to operate said regulator only in the event of relatively large power-circuit variations of appreciable duration, and comprising a plurality of electromagnets, means respectively controlled thereby having movements of different degree and contact mechanism governed by the operation 120 of said last-mentioned means.

8. In a regulator system, the combination 125

- with a power circuit and a regulator connected thereto, of control means for said regulator comprising a damped electromagnet, a pair of contact members controlled thereby, an undamped electromagnet and a pair of contact members controlled thereby, said contact members respectively traversing distances which differ with the different power-circuit variations to be corrected.
10. In a regulator system, the combination with a power circuit and an induction regulator connected thereto, of control means therefor adapted to operate said regulator only in the event of relatively large power-circuit variations of appreciable duration, and comprising a plurality of electromagnets, means respectively controlled thereby having movements of different degree and contact mechanism governed by the operation of said last-mentioned means, said electromagnets cooperating to selectively control the engagement of said contact members.
10. In a regulator system, the combination with a power circuit and an induction regulator connected thereto, of control means for said regulator comprising an electromagnet having a core armature, a pivoted, relatively long lever arm to one end of which said core armature is connected, an adjustable spring secured to the opposite end of said lever arm, a pair of spring-mounted contact members respectively located on opposite sides of said pivot, a second electromagnet having a core armature, a dash-pot mechanism co-operating with said core armature, a pivoted, relatively short lever arm to one end of which is connected the second-mentioned core armature, a pair of spring-mounted adjustable contact members carried by said arm and respectively located on opposite sides of said pivot and adapted to co-operate with the first-mentioned contact members, an adjustable spring co-operating with the opposite end of said relatively short lever arm, metallic plates respectively carried at opposite ends of said relatively long lever arm and electromagnets adapted to be selectively energized in accordance with the operation of said contact arm to co-operate with said metallic plates to thereby prevent chattering action of said contact members.
11. In a regulator system, the combination with a power circuit and an induction regulator connected thereto, of control means for said regulator comprising an electromagnet, a relatively long lever arm controlled thereby, an adjustable spring secured to said lever arm, a pair of contact members operated thereby, a second electromagnet having a dash-pot mechanism co-operating therewith, a relatively short lever arm controlled by the second-mentioned electromagnet, a pair of contact members controlled by said arm and adapted to co-operate with the first-mentioned electromagnets, an adjustable spring secured to said relatively short lever arm, and means for preventing chattering action of said contact members.
12. A relay mechanism comprising a damped electromagnet, an undamped electromagnet, a plurality of lever arms of different lengths respectively controlled by said electromagnets, a plurality of contact members controlled by said lever arms and a portion of which is adjustable, and means for preventing chattering action of said contact members.
13. In a regulator system, the combination with a power circuit, and an induction regulator connected thereto, of control means therefor comprising a plurality of members of unequal length, a plurality of contact members controlled thereby, and damped and undamped electromagnets adapted to operate said members whereby hunting action of said system is prevented.
14. In a regulator system, the combination with a power circuit and an induction regulator connected thereto, of control means therefor comprising a damped electromagnet, a relatively short arm controlled thereby, a pair of contact members controlled by said arm, an undamped electromagnet, a relatively long arm controlled thereby and a pair of contact members controlled by said arm, said electromagnets controlling said arms for actuating cooperating contact members toward each other at different rates of movement.
- In testimony whereof, I have hereunto subscribed my name this 8th day of June, 1922.
- EDWIN E. LEHR.
